SEPARATING DEVICE

Ralph B. Pressler, Fort Wayne, Ind., assignor to
 S. F. Bowser & Company, Incorporated, Fort
 Wayne, Ind., a corporation of Indiana

Application January 14, 1937, Serial No. 120,539

7 Claims. (Cl. 183—2.5)

The invention of the instant case is intended for use in dispensing systems which are adapted to handle liquids which, by reason of their viscosity, are apt to form with gases, including air, emulsions of great tenacity.

It is well known that the dispensing of liquids such as fuel oils, is generally carried on by passing the liquid to be delivered through a volume meter and the customer is charged in accordance with the reading on the meter. Most meters, however, will operate when air or emulsion is passed through them and consequently, unless all of the gases in the system are vented to atmosphere and unless all of the emulsion in the system has been broken down and the gases discharged to atmosphere before liquid reaches the meter, the record of the meter will not be a true indication of the amount of liquid dispensed.

It is an object of the present invention to provide a mechanism which will separate the gases from the liquid, close the dispensing line leading to the meter and which will vent a separation chamber to atmosphere when the liquid level in said chamber becomes so low that there is danger of gases or emulsion flowing to the meter.

Further objects of the invention are as follows:

To provide an emulsion breaking and gas separating device which is small enough to be used in installations where small size and low weight are important considerations.

To provide in a dispensing system a separating mechanism which will automatically terminate the dispensing operation when the quantity of emulsion in the separating chamber is excessive.

To provide in a dispensing system, a separating mechanism which will prevent a dispensing operation until the condition responsible for the emulsification of the liquid has been overcome.

To provide a combination screening and gas separating mechanism which is adapted for use in installations where size of equipment must be a minimum.

To provide in a dispensing system, a gas separating mechanism which will prevent the dispensing of gases or emulsion and which may be conditioned for operation after the disturbing condition has been remedied without shutting down the dispensing pump.

To provide in a dispensing system, a gas separating mechanism on the discharge side of the pump which will close the meter inlet when undesirable emulsion or gas conditions exist in the pump discharge line and which may be opened after correction of such conditions to re-establish

a flow of fluid without shutting down the pump.

To provide in a gas separating device, an unbalanced liquid outlet valve which is adapted to be automatically shut when the liquid level in the separating chamber drops, and which may be opened by a rising liquid level in said chamber only when the pressures in said separating chamber and the outlet line become balanced.

To provide a gas separating and emulsion breaking device having a separating chamber which is provided with a gas and a liquid outlet and float controlled valves for controlling said outlets.

To provide a gas separating and liquid screening device in which the screens are mounted for ready removability and are held firmly in operating position when in place.

To provide in a gas separating mechanism, a liquid outlet controlling, unbalanced, float controlled valve, together with means for protecting said valve while open, from the current of flowing liquid.

Other objects will become apparent from a study of the specification in connection with the accompanying drawings of which:

Figure 1 is a section of one form of separating mechanism taken on the line 1—1 of Figure 2.

Figure 2 is a section of the mechanism of Figure 1 taken on the line 2—2 of Figure 1, with some of the parts shown in full.

Figure 3 is an elevation showing the arrangement of the device of Figures 1 and 2 in a dispensing system.

Figure 4 is a central sectional view of a modified form of the separating device.

Construction—*Figs. 1, 2, and 3*

Referring to Figure 3, the liquid is stored in a tank 1, which may be a compartment of a truck tank or any other form of vessel which is connected by a suction line 3 to a pump 5 which is provided with the usual by-pass valve. The pump discharges through pipe 7 into a gas separating device 9 which is connected by means of a pipe 11, valve 13 and pipe 15 to the inlet side of a meter 17, which may be of any suitable kind. The fluid discharged from the meter after passing through a control valve 18 may be conducted away by any sort of a conduit such as the flexible hose 19, shown in Figure 3.

It is to be understood that instead of utilizing a pump 5 to create a flow of fluid through the system, any means of performing this task may be utilized. For example, the tank 1 may be sufficiently above the remainder of the system so

as to cause a flow of fluid by gravity there-through. Or again, pressure may be applied to the tank to force the liquid out through the system.

5 Referring to Figures 1 and 2, the gas separating mechanism comprises a body member 21, which is preferably of cast metal and which is provided with an inlet opening 23 and a liquid outlet opening 25. This body member is also provided with 10 a top opening 27 through which machining of the internal parts may be carried on and the discharge valve and its float and other elements may be inserted in the body member for assembly therein. Two side openings 29 and 31 are also 15 provided to permit the insertion of a screen which will be described below.

Cap members 33 and 35 are held in place by cap screws 37 to seal the openings 29 and 31 respectively, while a cap member 39 is held in position over the opening 27 by cap screws 41. The inlet and outlet pipes 7 and 11 are connected in any suitable manner to the inlet and outlet openings as, for instance, by means of flanges 43 and 45, gaskets 46, and cap screws 41.

25 The internal portion of the body 21 is divided into a plurality of chambers. Partition walls 49 and 51 at the outlet form a chamber 53. The wall 51 of this chamber is provided with a projection 55 which is perforated vertically as at 30 57 to form a guide for the pilot stem 59 of the valve 61. This valve serves to regulate a port 63 formed in the upper wall 49 of the chamber 53.

Valve 61 is provided with a small port 65 which is adapted to permit liquid to pass the valve and 35 enter chamber 53 for a purpose to be described.

The valve 61 is also provided with an upstanding stem 67 to which at its upper end is attached a float 69. Said stem 67 passes through a perforation 71 in a plate 73 which is supported at 40 a fixed distance above the wall 49 by means of shouldered studs 77 which are threaded at each end. One end of each stud is threadedly engaged in the wall 49 while the other end projects through said plate 73 and is surmounted by a 45 nut 79 which holds the plate in place against the shoulder of the studs.

Partition walls 81, 83 and 85, and a screen 87 serve to form an inlet chamber 89 and a separating chamber 91 in the body. The inlet comprises a U-shaped conduit, shown clearly in Figure 1, which communicates through openings in the ends of the troughlike screen receiving chamber, clearly shown in Figure 2. The open side or top of the trough-like chamber communicates 55 with the separating chamber 91.

The screen 87 comprises a pair of cylindrical heads 93 and 95 between which are mounted a pair of cylindrical screens. The outer screen 97 is of coarse mesh and of large wire and serves as 60 a support for the inner screen 99 which is of fine mesh and made of small wire. The screen 99 is the screening element.

The cylindrical heads 93 and 95 fit snugly into cylindrical bores in the partition 83 while the 65 flange 101 on head 95 seats in one or the other counterbores 103. The flange 101 is provided with a spider 105 which at its center is provided with a bore 107. A headed rod 109 is encircled by a helical spring 110 which is adapted to be 70 compressed between the head of the rod and the spider when the rod is inserted in the bore 107. A cotter pin 111 is passed through the rod to prevent it from coming out of the bore.

A sump 113 is provided in chamber 91 and a 75 drain plug 115 is provided to close an opening

which leads from the sump to the outside of said body.

The baffle 117 extends transversely of the chamber 91 and serves to protect the float 69 from a direct flow of the liquid against it. This baffle also tends to prevent a direct flow of liquid to the valve, and since some of the liquid is thus compelled to follow a more circuitous path, a longer period during which separation of gas may occur is provided.

The cover plate 39 mentioned above has an opening 119 leading from chamber 91, which opening is internally threaded to receive a threaded portion of the valve body 121. A boss 123 is also provided on the cover plate and is 15 adapted to support a bracket 125 upon which is mounted the float and valve mechanism.

A valve seat 127 is provided in the valve body 121 and a valve 129 is slidably mounted in a bore of said valve body. This valve is provided with 20 guide fins 131, which do not close the bore but which permit communication between chamber 91 and a chamber 133 which lies between the upper and lower coaxial bores in the valve body.

The valve 129 is provided with an axial bore 25 135 which is restricted at its upper end to provide a seat for the needle valve 137 which is slidably mounted in said bore. A collar 139 is pinned to said needle valve and rides in an opening in the valve 129 which is longer than said collar. The collar contacts the upwardly facing wall of 30 said elongated opening to limit the axial motion of the needle valve. Sufficient play is allowed between the collar and said walls due to the elongation of the opening to permit full opening and 35 closing movement of the valve.

A transverse bore 141 is provided in the valve 129 and enters just below the seat of the needle valve so that when the valve 129 is closed against its seat 127, and when the needle valve 137 is open, the chamber 133 will be connected to the outlet bore 143.

The bracket 125 is provided with a pivot pin 145 to which is pivoted a lever which has a float carrying arm 147 and a stop carrying arm 149. The arm 147 is provided with a float 151 while the arm 149 has threadedly engaged therewith a headed stop screw 153 which is held in adjusted position by a nut 155. A stop arm 157 is provided on the bracket and it is against this that the screw 153 abuts.

The needle valve 137 is provided at its lower end with a square portion 157 which is provided with an elongated transverse slot 158. A headed pin 159 is inserted through the slot and through a perforation in the float lever 147 and receives a cotter pin which is adapted to prevent withdrawal of the pin from the various elements. The slot is larger than pin 159 hence considerable motion of float 151 is permitted before valve 137 is operated.

It is to be noted that the float 69 is of such specific gravity that it will float only in liquid while the float 151 is of such specific gravity that it will float either in liquid or in an emulsion of liquid and gas.

Operation

To operate the system disclosed above and shown in Figure 3, it will be necessary to start the pump and discharge liquid into the separator and the rest of the system to eliminate gases therefrom. The liquid discharged from conduit 7 into chamber 89 passes through the screen 87, which holds back any dirt, etc., which may be in

the liquid, and into the separating chamber 91 which is of such size that the velocity of flow is substantially reduced and this in turn permits any gases which are entrapped in the liquid to separate therefrom. If there is a substantial amount of gas in the liquid and the latter is viscous, there will be a layer of an emulsion or foam of gas and liquid above the liquid level. This must not be permitted to pass through the vent because a considerable loss of liquid which forms the emulsion would result.

10 The liquid, which is now substantially free from entrapped gases, is discharged through valve 61 and chamber 53 into conduit 11 from which it may flow through the remainder of the system.

15 During the regular dispensing operation, once the system has been filled with liquid as described above, so long as quantities of gas introduced into the separating chamber 91 are such that 20 they can be vented by valve 129, the liquid level and usually the emulsion or foam level will remain at such stages that valve 61 will be held against shield 73 by its float 69 so that the current of liquid flowing into chamber 53 will not 25 carry the valve to its closed position and the float 151 will occupy its lowest position which is regulated by contact of stop 153 with abutment 157.

30 If the quantity of gas introduced into chamber 91 is small, there will be a tendency for the liquid level to rise; and if there is a normal, or less than normal, amount of emulsion, the rising liquid level will cause float 151 to rise, turning lever 147 clockwise about pivot 145. This motion 35 of the lever will first take up the lost motion between pin 159, portion 157, needle valve 137 and its seat to close the valve and thereafter the valve 129 will rise into contact with its seat 40 127 to prevent any discharge of fluid whatever from chamber 91, thus preventing any loss of emulsion or liquid through the vent.

45 As more gas separates from the liquid in chamber 91 the liquid level will be forced down and the valves 137 and 129 will open in a manner to be described below. But before considering the opening of the valves, we shall consider how, under different circumstances, they may be closed.

50 If we suppose that the liquid stands at its normal level so that float 69 holds valve 61 against shield 73 but that float 151 is not operated by the liquid level, but that due to some cause an abnormal amount of emulsion is formed in the chamber. As the level of the foam or emulsion rises, float 151, which is adapted to rise with the emulsion, is operated and the valves 137 and 129 are operated in sequence as just described in connection with the rise of the liquid level.

55 Usually the pumping of a great quantity of gas into chamber 91 accounts for a large quantity of emulsion in the chamber and as a result not only 60 are the valves 137 and 129 closed by the high level of the emulsion as just described, but the liquid level is simultaneously depressed, and consequently the float 69 will gradually drop until 65 valve 61 contacts its seat and closes compartment 53 off from chamber 91. As a result of the closing of this valve the only flow of fluid from the separating device will be that through the opening 65 which passes such a small amount of fluid that there is little danger of emulsion reaching the meter. The operator must perform certain operations described below to again start the full flow. The closing of valve 61 is necessary to prevent pumping of gases or emulsion to the meter.

70 In any of the cases mentioned in which the valves 137 and 129 were closed either by a rising liquid level or by a rising emulsion level, the valves will be opened when the level of liquid or emulsion drops. In the case of the emulsion, it is broken down in time due to the separation of the liquid from the gas and the float will drop. Since float 151 is adapted to rise in an emulsion, it is obvious that it must be very light and it is, consequently, unable to overcome the force which 75 holds valve 129 against its seat. This force comprises the by-pass pressure of the pump which is usually about fifty pounds to the square inch acting upon the cross-sectional area of the valve.

76 The needle valve 137 having a relatively much 15 smaller area than valve 129 may be operated by the weight of float 151 and its associated parts. As the float 151 drops, the valve 137 opens to permit the gases entrapped under pressure in chamber 91 to flow into chamber 133 in the valve body and thence through the transverse bore 139, past the needle valve port and into the vent 143. As the pressure on opposite sides of valve 129 approaches equalization and as the force exerted on the valve is reduced due to the reduction in effective area caused by the opening of valve 137, the valve 129 is opened by the weight of the float 151 and its associated parts. The lost motion permits sufficient lowering of the emulsion level to insure that little emulsion will 30 be lost through the vent as valves 129 and 137 open.

35 In the case of the low liquid level last described, the venting of gases from the chamber 91 as just described, permits fluid to discharge 40 into said chamber from the pump to make up the deficiency, and the liquid level will rise to a level at which it is capable of supporting the float 69. The float, however, is not capable of lifting the valve 61 which is an unbalanced one, 45 against the full by-pass pressure, hence the operator must close the valve 13 to enable pressures on opposite sides of the valve 61 to become balanced by a passage of fluid through the opening 65 in the valve. As soon as the pressures in 50 chamber 53 and 91 become equalized the float 45 will lift the valve to open it, and further dispensing of liquid will be permitted as soon as the operator opens valve 13.

55 It is obvious, however, that unless the conditions such as a leaky pump suction line, etc., 50 which caused the high degree of emulsification is corrected, the dispensing operation will be of short duration because as soon as the liquid level again drops, the valve will again close and the operator will have to repeat the process just described.

60 It is apparent that the valve 61, which operates in conjunction only with the liquid level, will be closed and the greater part of the liquid discharge will be terminated as soon as the level within the chamber 91 drops to a level at which it is incapable of supporting the float 69 65 irrespective of whether the valves 129 and 137 are closed or open. It is also obvious that each time the valve 61 closes, the pump pressure will hold it shut until pressures on both sides of the valve are equalized.

70 The lowest position of float 151 is regulated by the contact of the adjustable stop 153 and the abutment 157. By loosening nut 155 and screwing the stop into or out of lever 149, the lowermost position of float 151 may be adjusted.

Structure of modification—Figure 4

75 The modified form of separator which is shown

in Figure 4 is used only in connection with gravity systems, such as installed in the usual tank truck. It is not adapted for use with a pump or in any system in which the liquid may be forced through the system under comparatively high pressures, that is, pressures above five pounds to the square inch.

The device comprises a body member 161 which is divided internally into three compartments. Partition walls 163 and 165 together with screen 167 form an inlet compartment 169 while partition walls 171, 173 and 175 form an outlet compartment 177. The remainder of the body forms a separating chamber 179. The walls 171 and 175 are provided with ports 181 and 183 which are in axial alignment and are adapted to receive valves 185 and 187 which are arranged in spaced co-axial relation upon a valve stem 189. The lower end of the valve stem is adapted to engage an abutment 191 to limit the downward motion of the valves, and when the stem is in its lowermost position, the valves 185 and 187 fully close the ports 181 and 183 respectively. The valves are provided with guide fins 193 which engage the ports and maintain the valve stem in its coaxial relation with respect to the ports.

A float 195 is connected to the upper end of said valve stem. This float is of such a specific gravity that it will float in liquid. An upwardly extending and vertically movable valve 197 is connected by means of a link 199 to the top of said float so that this valve too, will be operated by said float.

The chamber 177 is provided with an outlet opening 201 to which may be connected in any suitable manner, an outlet conduit 203. Chamber 169 is provided with an inlet opening 205 to which may be connected in any suitable manner the inlet conduit 207. This chamber is also provided with an opening 209 which is normally closed by means of a cap 211 held in place by cap screws 213. The latter opening is provided to permit ready insertion and removal of the screen 167.

The wall 165 is provided with an opening 215 which is counterbored as at 217. The screen is in the form of a cylinder, one end of which is closed and the other end of which is provided with a ring 219 having a flange 221. The ring 50 and flange are adapted to fit snugly in the opening 215 and the counterbore respectively to prevent the passage of liquid through the opening. An upwardly extending spider 223 is fixed to the flange 221. The hub 225 of the spider is provided with an axial opening which is adapted to receive a headed pin 227. A helical spring 229 is confined between the head of said pin and the spider, and a cotter pin 231 prevents withdrawal of the pin from the hole in said spider.

As shown in Figure 4, the cap 211 when it is drawn to its seat by the cap screws, compresses the spring 229 against the hub of said spider and consequently holds the flanged ring against its seat in the wall 165 to hold the screen in its operative position.

The screen 167 is composed of an outer screen 233 of large wire and large mesh, which serves to support the inner screen 235, which is of small wire and fine mesh, against distortion by the flow of liquid.

An opening 237 is provided at the top of the separating chamber 179 to facilitate machining of the valve seats, etc., and to permit ready assembly of the parts within said chamber. The 75 opening is provided with a cap 239 which is

adapted to seal the openings and cap screws 241 are provided to hold the cap in position over the opening. In the case of all of the covers and flange joints, etc., gaskets are usually provided as shown to seal the joints.

The cap 239 is provided with a threaded opening 243 which is adapted to receive the threaded portion of a valve body 245. The valve body is provided with a guide 247 for the stem 249 of valve 197 and with a seat 251 for said valve. A threaded outlet 253 is provided for the reception of a vent pipe.

At the bottom of the chamber 179 directly beneath screen 167 is a drain outlet which is closed by a plug 255. It will be noted that the wall 163 of chamber 169 is extended downwardly beyond the wall 165 as at 257 and serves as a baffle to protect the float 195 against the direct flow of fluid.

Operation

Liquid will flow by gravity from the storage tank (not shown) through pipe 207 into the intake chamber 169 as indicated by the arrow in this chamber, and thereafter through the screen 167 into the separating chamber 179. The screen will retain any particles of dirt, etc., which may be in the liquid and this dirt may be removed from the device by simply removing the cover plate and cleaning the screen at a time when no liquid is being supplied to the device.

In the separating chamber which is large enough to materially reduce the velocity of the liquid, the entrapped gases are given an opportunity to separate from the liquid before it flows to the outlet conduit 203 and to the meter (not shown) which is connected to the outlet conduit.

The liquid level is forced down when a greater quantity of gas is introduced into the separating chamber than can be discharged through the vent 253. However, when the quantity of gas supplied to the chamber is smaller than that which can be discharged from the vent, the liquid level will rise. To prevent discharge of liquid from the vent, the valve 197 is closed by the float which rises with the rising liquid level and the valve remains closed until a quantity of gas sufficient to lower the liquid level accumulates in the chamber 179.

The liquid level in the chamber 179 also controls the valves 185 and 187 so that should the liquid level become so low, during a dispensing operation, as to be unable to support the float 191, the valve rod 189 will move downwardly into abutting relation with stop 191 and the valves 185 and 187 will be closed, so as to prevent the passage of gas or emulsion into the conduit 203 and hence to the meter.

If the liquid level again rises sufficiently to support the float 195, the valves 185 and 187 will again open to permit a flow of liquid from chamber 179. Since the pressures on the valves 185 and 187 are balanced, the valves will open as soon as the liquid level is high enough to buoy up the float.

It is to be understood that the word "gas" is used to indicate any form of gaseous substance which is entrapped in the liquid, and is to include air and vapors.

It is apparent that changes may be made in the form, construction and arrangement of parts without departing from the spirit of the invention and the right is reserved to make all such changes as fairly fall within the scope of the appended claims.

Having thus described my invention, what I

claim as new and desire to secure by Letters Patent of the United States is:

- 5 1. In a separating system the combination of a source of fluid, comprising gas, liquid and emulsion, under pressure, a separating chamber connected to receive fluid from said source, said chamber having gas and liquid outlets, valve means for regulating said gas outlet, an emulsion level responsive float connected to operate said valve means, said valve means being so constructed and arranged as to open said outlet against full pressure in the chamber as said float falls and to close said outlet as it rises, an unbalanced valve for said liquid outlet adapted to close in the direction of the flow of liquid from the chamber, a liquid level responsive float connected with liquid outlet, a shut-off valve in said conduit, and means for by-passing said unbalanced valve.
- 10 2. In a separating system the combination of a source of fluid under pressure, a separating chamber connected to receive fluid from said source, said chamber having gas and liquid outlets, valve means for regulating said gas outlet, an emulsion level responsive float connected to operate said valve means, said valve means being so constructed and arranged as to open said outlet against full pressure in the chamber as said float falls and to close said outlet as it rises, an unbalanced valve for said liquid outlet adapted to close in the direction of the flow of liquid from the chamber, liquid level responsive float means connected to operate said valve and having power sufficient only to overcome the weight of the valve, and means for balancing the pressures acting on said valve.
- 15 3. In a separating device adapted for use in a system having a source of fluid comprising gas, liquid and emulsion under pressure, the combination of a separating chamber connected to receive fluid from said source, means forming gas and liquid outlets from said chamber, an unbalanced valve for said liquid outlet, a liquid level responsive float connected with said unbalanced valve, an emulsion level responsive float, valve means adapted to control said gas outlet, and means connecting said emulsion level responsive float and said valve means, said valve means being so constructed and arranged as to open under the weight of said emulsion level responsive float against full pressure in the chamber.
- 20 4. In a separating device adapted for use in a system having a source of fluid comprising gas, liquid and emulsion under pressure, the combination of a separating chamber connected to re-

ceive fluid from said source, means forming gas and liquid outlets from said chamber, and unbalanced valve for said liquid outlet, a liquid level responsive float connected with said unbalanced valve, an emulsion level responsive float, valve means adapted to control said gas outlet, and means connecting said valve means for operation by said emulsion level responsive float, said valve means comprising a small valve of such area as to be responsive to the weight of said emulsion level responsive float against the maximum differential pressure imposed across said gas outlet and a large valve of such area as to be responsive to the weight of said emulsion level responsive float against the differential pressure imposed across said gas outlet when said small valve is open.

5 5. In a separating device adapted for use in a system having a source of fluid comprising gas, liquid and emulsion under pressure, the combination of a separating chamber connected to receive fluid from said source, means forming gas and liquid outlets from said chamber, an unbalanced valve for said liquid outlet, a liquid level responsive float connected with said unbalanced valve, a shield, means for mounting said shield adjacent the valve open position of said unbalanced valve up stream of said valve, an emulsion level responsive float, valve means adapted to control said gas outlet, and means connecting said emulsion level responsive float and said valve means, said valve means being so constructed and arranged as to open under the weight of said emulsion level responsive float against full pressure in the chamber.

20 6. In a gas and liquid separator, a separating chamber, means forming a liquid outlet port for said chamber, a poppet type valve mounted for movement between port open and port closing positions, a liquid float, means for connecting said float to operate said valve, a shield disposed parallel to and upstream of said valve, and means forming an opening in said shield to provide passage for said connecting means.

25 7. In a gas and liquid separator, a separating chamber, means forming a liquid outlet port for said chamber, a poppet type valve mounted for movement between port open and port closing positions, a liquid float, means connecting said float to operate said valve, a shield for said valve and means for supporting said shield immediately adjacent the port open position of said valve and parallel thereto.

RALPH B. PRESSLER. 35
